(57) **CLAIM**

We claim, the ornamental design for a no-contact tool, as shown and described.

DESCRIPTION

FIG. 1 is a perspective view of a no-contact tool, showing our new design;

FIG. 2 is first side plan view thereof;

FIG. 3 is a opposite side plan view thereof;

FIG. 4 is first edge plan view thereof;

FIG. 5 is a opposite edge plan view thereof;

FIG. 6 is a top edge plan view thereof; and,

FIG. 7 is a bottom edge plan view thereof.

The broken line showing of a no-contact tool is included for the purpose of illustrating portions of the article and forms no part of the claimed design.

1 Claim, 5 Drawing Sheets
